CLAIM

The ornamental design for a red light therapy device, as shown and described.

DESCRIPTION

FIG. 1 is a perspective view of a red light therapy device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear side perspective view thereof;

FIG. 9 is an enlarged detail view of area 9 shown in FIG. 3; and,

FIG. 10 is an enlarged detail view of area 10 shown in FIG. 8.

The broken lines in the drawings depict portions of the red light therapy device that form no part of the claimed design. The broken line circle in FIGS. 3, 8, 9 and 10 defines the bounds of the enlargement and forms no part of the claimed design.
